BUILDING CONSTRUCTION

Harry N. Atwood and Nellie Dow Atwood, Berlin, N.Y.

Application September 20, 1956, Serial No. 611,017

1 Claim. (Cl. 20—2)

This invention relates to the construction of an edifice. More particularly, the invention is concerned with the use of specially constructed hollow components as the principal elements for construction of substantially all of an entire building. The buildings may be dwellings, commercial structures, and in fact, a wide variety of utilitarian structures.

An important element of the invention is in the hollow components, referred to for convenience, as tubes, which are comprised essentially of an inner or hollow core member which is reinforced by an outer, or as desired, both an inner and an outer covering of a plastic material. These plastic reinforced cores are given such added strength by the plastic covering as to be usable in the construction of all parts of an edifice where the core members would otherwise fail to possess the requisite strength factors. However, as hereinafter set forth, the plastic must possess certain characteristics and must be bonded to the core in a specific manner.

The tubes in this invention are utilized in joined multiples for the construction of the floors, walls, ceilings, roof, columns, joists, for framing the openings, making the doors and windows, skylights, and other elements of a building which might ordinarily be made of solid wood, steel, bricks, lumber, cement, and other customary conventional materials, and yet will possess the essential strength factors, while at the same time with only a fraction of the usual weight mass.

This invention makes possible the use of materials which otherwise would be unsuitable for the purposes herein utilized. It also eliminates any need for the use of decorative coatings and provides for permanent decorative finishing of the interior and exterior of the buildings.

The invention is distinguished from and must not be confused with the heretofore known constructions involving the uses of hollow tiles, or juxtaposed hollow masonry elements which are laid up or joined with Portland cement or the like, to construct only certain portions of a building and which necessarily involve skilled labor. In this invention, the building can be constructed in much less than the time required for ordinary conventional construction and with a minimum of any skilled labor. At the same time the use of the invention reduces costs to a considerable degree in other respects.

A building constructed in accordance with this invention is fire resistant, lightweight, has inherent insulating properties, and is free from damage by insect or parasite attack, as well as free from numerous other deterioration factors of ordinary conventionally constructed buildings. The expense factors both as to construction and maintenance of a building constructed in accordance with this invention are minor in comparison to conventionally constructed buildings.

The invention makes possible the construction of buildings not only of conventional design but also of designs unique and not otherwise possible at low cost. Buildings constructed pursuant to this invention are suitable for

2

use in a variety of climates and are not affected by temperature changes within a range as great as 350 degrees Fahrenheit to 140 degrees below zero Fahrenheit. Consequently, no changes of temperature within the extreme ranges thereof ordinarily encountered in a dwelling, or most commercial or industrial structures, will have any adverse effects. Due to the mode of construction employed in this invention, the building remains dry and is not affected by even the running of heavy moisture through those of the tubes employed in which the core is covered both on the inside and on the outside with the plastic, as hereinafter more specifically described.

The hollow cores make possible the use of the tubes or any desired ones thereof as conduits for carrying pipes, wiring, and the like, and are themselves usable as water conduits, heating, and air-conditioning, so that any desired parts of the floors, walls, or ceilings, or any partitions, can be made to serve for the distribution of heating or cooling. At the same time, since according to this invention, there is no limitation as to cross-sectional configuration of any or all of the tubes, nor any limitation as to color schemes, or as to which of the tubes are opaque or as to which are either wholly or partly translucent or transparent, selected ones of assembled multiples of the tubes can be used to admit light or serve as windows in any parts of the building. Also, any of the tubes desired to be so used can serve as housings for lighting.

When the cores are plastic reinforced, as hereinafter described, they possess great compressive strength and the cores need not be of great thickness while at the same time, the plastic in comparison to the thickness of the core will need be only fractionally as thick. When the tubes are joined, in multiples in the manner herein described, the strength is multiplied beyond the mere sum of the components. When the cores are reinforced with plastic, both interiorly and exteriorly, the strength factor, compressive and otherwise, is even more greatly increased. The core is actually locked in. Any core to which the plastic is applied as a reinforcement has a skin-stress strength which will prevent buckling under loads otherwise sufficient to cause rupture.

It is important to note that in this invention, the plastic is the reinforcement for the core, contrary to mere reinforced plastics, such as commonly known.

Since the plastic can be any of a variety of colors or color combinations and has a tough, wear-resistant, water repellent characteristic, as well as the ability to remain unaffected by weather conditions within the temperature ranges foregoing described, no decorative exteriorly applied extraneous coatings, such as paint, etc., are required. The decoration is a permanent part of the building.

Other advantages and further objects of the invention will be readily apparent from the appended drawings and detailed description, given as an illustrative embodiment.

In the drawings:

Figure 1 is a perspective view of a building constructed in accordance with the invention, part of the roof being omitted to disclose the interior.

Figure 2 is a view showing in perspective and partly in section one way of assembling components of the building.

Figure 3 is a view showing in perspective and partly broken away, of each of a representative group of various configurations of the hollow components used in this invention.

Figure 4 is a fragmentary elevation showing a transparent or translucent hollow component as a part of a multiple assembly.

Figure 5 is a section on line 5—5 of Figure 4.

Figure 6 is an elevational view showing a group of

transparent or translucent hollow components used as a window.

Figure 7 is a detail sectional view on line 7-7 of Figure 6.

Figure 8 is a detail vertical sectional view showing a means of loading certain of the hollow components for a foundation or added stability.

Figure 9 is an elevational view of another form of window.

Figure 10 is a detail sectional view on line 10-10 of Figure 9.

Figure 11 is a detail perspective view illustrating a hollow component used as a pipe conduit.

Figure 12 is a view similar to Figure 11 showing use of a hollow component as a housing for a lighting means.

Figure 13 is a view similar to Figures 11 and 12 showing use of a hollow component as a duct for heating or air-conditioning.

Figure 14 is a detail sectional view showing a form of construction for a skylight, or the like.

Figure 15 is a detail sectional view on line 15-15 of Figure 1.

Figure 16 is an enlarged detail sectional view showing two of the hollow components joined by fusing.

Figure 17 is a view similar to Figure 16 showing another means of connecting the hollow components to each other.

The building shown in Figure 1, indicated generally at 10, represents a dwelling which obviously may have any desired configuration and may be constructed according to any desired architectural plan. Hence, the dwelling shown in Figure 1 is merely by way of general illustration.

The building 10 has a roof 11 which in Figure 10 is shown as only partially completed in order to disclose a representative portion of the interior generally indicated at 12. The roof 11 has a skylight 14 which may be located in any portion of the roof and made of any size or configuration. The skylight 14 is constructed of a multiple of joined building components 15 which will be further herein described in greater detail. These components 15, for purposes of the skylight structure and for other purposes which will become apparent, may be either wholly or partially transparent or translucent and may be alternated with opaque similar components. Other portions of the roof 11, likewise constructed of joined components 15 may be of opaque or transparent or translucent materials. For purposes of reference one of the components 15 has been numbered but it will be understood that this numeral represents all the components generally except as other identified.

The entire dwelling 10 is constructed of the joined multiples of components 15, including the windows 16, walls 17, partitions 18, floors 19, and such other customary structural elements as would ordinarily involve plaster, wood, metal, bricks and other conventional materials. As seen in Figure 1, the components 15 are of a generally rectangular cross-sectional configuration. However, as illustrated in Figure 3 a variety of other shapes, such as 15a, 15b, 15c, 15d, and 15e, may be employed, as well as numerous others, limited only by whatever shape or configuration may be desired.

The components 15, herein sometimes referred to for convenience of reference as tubes, are comprised of an inner element 20, and an outer element 21 referred to as a plastic covering or skin. Each tube 15 or any of them, may also have an inner covering or plastic skin 22, as shown in the cross-section of some of the tubes seen in Figure 5, wherein one of the tubes has such inner skin 22 and the others have only the outer skin 21. These tubes or components, insofar as the core or inner element 20 is concerned, may be of natural or synthetic fibrous, porous, or otherwise formed materials which of themselves do not possess the requisite strength factors for the purposes herein employed, but when they are reinforced and strengthened by either the inner skin 22 and outer skin 21 as shown in Fig. 15, or merely the outer skin 21,

they are then usable for purposes, where previously, metal, solid lumber, or built-up materials have to be employed.

Taking, for example only, such a material as the well known "Celotex," or composition board, and reinforcing it with the plastic skin 21 or skins 21 and 22, these skins being relatively extremely thin in comparison to the thickness of a wall of the core 20, a hollow building component 15 is created which as heretofore explained possesses great strength. The plastic skin is bonded to the core 20 by the application of heat to the skin. The temperature to which the plastic is subjected is about 350 degrees Fahrenheit or until the plastic becomes sticky or tacky. This heat need only be applied for a matter of a few seconds and the skin pressed tightly to the core. The skin is smoothed so as to be free of wrinkles and to remove any air bubbles or pockets. When the skin has been smoothly adhered to the core, the heat is removed. The skin sets and adheres to the core almost instantly, usually in two or three seconds.

20 The plastic employed is a polymeric ester, that is a polyester resin, more particularly such as polyethylene terephthalate, which has the property of being unaffected by extremes of temperature ranging from as great as about 350 degrees above zero Fahrenheit to 140 degrees below zero Fahrenheit and is invulnerable to insect and vermin attack, is moisture repellent, and possesses great strength and resistance to tearing, fracture, and bursting. A component 15 constructed as herein described and of the same outer dimensions as for example, a piece of the same dimensioned solid lumber possesses greater strength.

25 The components 15, for the purposes herein described, of constructing the building 10 are employed in joined multiples. The components are joined and integrated by means of their skins 21, by temporarily heating the skins 35 until tacky or sticky as hereinbefore explained and pressing the skin surfaces to each other. In the example shown in Figure 2, the components may be arranged and integrated in edge-to-edge relationship with their ends 23 closed by inserts 24 or seated in channels 25 which may 40 simply be halves of components 15 of suitable dimensions. Completed assemblies may have corners 28 added thereto and these may also be formed from a component 15. The channels 25 may be cut away as at 29 to provide a suitable joint.

45 An illustration of an assembly of tubes 15, with a transparent or translucent tube between two opaque tubes is seen in Figure 4.

As seen in Figure 7, tubes 15 are of an inner core and an outer plastic skin as before described, or as desired, 50 when certain of the tubes are transparent or translucent, such a tube 30 may be of entirely reinforced plastic in which the skin is bonded to the core and in effect fused therewith so as to become a laminated composite of plastics in the form of a hollow tube or component for present purposes.

In Figure 8, components 15, joined with each other, are loaded with concrete or other filler 32 to form a foundation or to give additional stability to a portion of the building.

60 Figures 9 and 10 illustrate a form of window 16 in which what would ordinarily be a framed glass is actually a sheet of plastic 31 retained in and joined with components 15 in the same way as the components 15 are themselves bonded or joined to each other to form multiples.

65 Figures 11 and 12 respectively illustrate how a pipe 33 may be inserted through the hollow center of a component tube 15 or a lighting tube 34 placed within a translucent or transparent component 15 so as to serve for illuminating desired portions of the building. Figure 13 illustrates how a hollow component 15 may serve 70 as a duct for heat, air, cooling, or fluid transmission.

Figure 14 illustrates how the components, in various shapes, may be joined to form a skylight 14.

Figures 16 and 17 illustrate a detail of the skin joining of components 15. As seen in Figure 16, the skins

are virtually fused, whereas in Figure 17, the bond is formed by means of a plastic cement 36 which gives the same functional results. This type of cement may be sprayed on skins to be joined, and sets instantly to form a permanent bond such as the bond formed by the other method of joining herein described.

It is important to note that the entire building is formed of joined hollow plastic-reinforced components in which the plastic is a reinforcement as distinguished from a reinforced plastic.

In constructing a building in accordance with this invention, the components are pre-formed in the desired shapes for the various parts of the building, cut where necessary for special interfitting, and are joined to form the walls, roof, windows, doorways, and the like, for the building. As the whole procedure is merely that of bonding one tube to another, a minimum of skilled labor is required. Any errors are easily rectified by readily removing and inserting tubes. The doors, panels, and any trim components are formed entirely of tubes joined to the desired dimensions. Room plans are a matter of choice and may easily be altered at any time, during construction, or after the building is constructed. Removal of a tube or portion thereof does not affect the rest of the structure. Color and other decorative schemes are obviously unlimited. Painting is not required since the finish is built-in with the plastic skin. Special conduits for utilities and other functional purposes are not required since any tube may serve. Also closing the tubes at the ends will provide sealed dead-air insulation. Conversely, any desired ventilation may be had by opening or leav-

ing open ends on any of the tubes, without adverse effects on the remainder. In short, for the first time, a building is provided which is so unique as to defy comparison with any prior known construction.

Since each unit is essentially its own load bearing member, having an additional strength factor derived from adjacent ones of the multiples of tubes, special load bearing members will not generally be required, as for example, to take care of a snow load on the roof, or for instance in the pressure forces exerted by high winds and unusual strains and stresses.

What is claimed is:

A building construction including a plurality of pre-formed structural building elements with each of said elements comprising an elongated tubular body, a plastic sheet adhesively secured to the inner surface of said body, and a plastic sheet adhesively secured to the outer surface of said body for reinforcing said body, said elements being secured together by adhesion of the plastic sheets secured to their outer surface, said plastic sheets being formed of polyester resin and said body being formed of a porous fibrous mass.
